LEVELING MACHINE

Fred V. Hart, Lynn, Mass., assignor to United
Shoe Machinery Corporation, Flemington, N. J.,
a corporation of New Jersey

Application September 5, 1947, Serial No. 772,271

6 Claims. (Cl. 12—34)

1

This invention relates to machines for operating on shoes and more particularly to mechanisms for shaping or leveling the bottoms of shoes. The invention is herein illustrated with reference to a fluid-pressure-operated leveling machine of the type illustrated in Letters Patent of the United States No. 2,230,244, granted February 4, 1941 in the names of Fred V. Hart and John J. Austin.

Machines of the type disclosed in the aforementioned patent are provided with a leveling roll which is held by springs during the leveling operation in engagement with the bottom of an inverted shoe. The shoe support is moved under the control of the operator by a fluid-pressure motor in directions lengthwise of a shoe on the support. Upon movement of the shoe support to carry the toe end of the shoe under the leveling roll from a position forwardly thereof a fluid-pressure motor is operated to lift the roll against the action of the springs, and the roll is similarly lifted by the fluid-pressure motor when the support is swung forwardly to carry the toe end of the shoe out from under the roll, thereby to prevent the application of pressure to the extreme toe end of the sole of the shoe which would roll the edge of the sole upwardly and detract from the appearance of the shoe.

Pressure fluid is supplied to the motors by a pump under the control of a pressure-regulating valve which is operated automatically during movement of the shoe support into its forwardmost position, to by-pass pressure fluid from the pump to a reservoir. Consequently with the support in its forward position the pressure of the fluid in the roll-lifting motor drops and is unable to sustain the roll in its elevated position against the action of the springs. It is therefore important that the roll be again lifted before the support is moved rearwardly far enough to carry a shoe beneath the roll, thereby to avoid damage to the toe end of the sole of the shoe.

Heretofore this has been accomplished by operating the pressure-regulating valve during the initial rearward movement of the shoe support whereupon the pressure fluid operates the roll-lifting motor to elevate the roll. Since some motion of the shoe support is required to operate the pressure-regulating valve and because of the further fact that the roll must be elevated a considerable distance to permit passage of the toe end of the shoe thereunder, it sometimes happens that an operator will cause the shoe support to be moved rearwardly at such a fast rate of speed that the toe end of the sole of the shoe will

2

strike against the leveling roll before the roll has been elevated sufficiently by the roll-lifting motor. Also, if the shoe has been accidentally located on the support with the toe end of the shoe nearer the roll than its proper position on the support the same result may happen.

In order to eliminate this possibility of damaging the shoe at the beginning of the leveling operation, and in accordance with an object of the present invention, mechanism is provided for maintaining the leveling roll in its elevated position during those periods that the shoe support is located in its forward position for the removal of a shoe therefrom and the positioning thereon of another shoe the bottom of which is to be leveled. This is accomplished in accordance with a feature of the invention by providing locking means which is rendered operative during the latter portion of the forward movement of the shoe support to lock the roll in its elevated position, and to maintain it in such position until the shoe support has again been moved rearwardly whereupon the locking means is released and the roll is held by fluid pressure in elevated position until the toe end of the shoe passes thereunder whereupon the roll is pressed against the shoe bottom by the springs.

In accordance with a further feature of the invention the roll-locking means is rendered effective only after the roll has been elevated by the roll-lifting motor heretofore referred to and before the pressure-regulating valve has operated to cut off the supply of pressure fluid to the motor.

35 The above and other features of the invention, including various details of construction and novel combinations of parts will now be described with reference to the accompanying drawing and pointed out in the claims.

40 In the drawing,

Fig. 1 is a view in right-hand side elevation of a machine in which the invention is embodied, parts of the structure being broken away and other parts being shown in section; and

45 Fig. 2 is a detail view on a larger scale of a portion of the mechanism shown in Fig. 1, the parts being in the positions assumed during the leveling operation.

50 As shown in Fig. 1 the machine includes a shoe support or jack 10 pivoted on a shaft 12 for movements lengthwise of a shoe on the support to carry the shoe rearwardly and forwardly beneath a leveling roll 14. This roll is mounted for turning movements on a rod 16 carried by a holder 18 which is pivotally connected at 20 to

a carrier 22. The carrier is mounted for tipping movements laterally of the machine about the axis of a forwardly and rearwardly extending shaft 24 supported in bearings, one of which is indicated at 26 at the top of the machine.

The holder 18 has a rearwardly extending arm 28 connected by a short link 30 to the rearwardly extending arm 32 of a bell crank lever 34 fulcrumed at 36 to the carrier 22. The bell crank lever has downwardly extending arms 38 carrying trunnions 40 extending into a circumferential groove 42 in a bushing 44 slidably mounted on the shaft 24. Pivotally mounted on a laterally extending shaft 46 supported by suitable bearings in the frame of the machine is an upwardly extending arm 48, the upper portion of which carries trunnions 50 extending into a circumferential groove 52 in the bushing 44. Mounted on the shaft 46 is a downwardly extending yoke 54 to which is connected by a threaded rod 56 a yoke-shaped member 58 in which is pivoted a lever 60. This lever has oppositely extending arms of equal lengths to the ends of which are pivoted blocks 62 providing abutments for compression springs 64, 66, the latter bearing against an abutment 68 pivoted at 70 to the frame of the machine. The spring 64 at its upper end engages an abutment 72 pivotally connected to an arm 74 integral with the arm 48. These springs 64, 66 act to rock the arm 48 in a clockwise direction moving the bushing 44 rearwardly along the shaft and urging the roll 14 downwardly to exert leveling pressure against the shoe bottom.

Provision is made for lifting the roll 14 against the action of the springs 64, 66 when the support 10 is moved to carry the toe end of the shoe forwardly of the leveling roll and whenever, during the leveling operation, it is desired to lift the roll out of contact with the shoe bottom. Integral with the arm 48 is an arm 76 connected by an adjustable link 78 to one end of a lever 80 pivoted intermediate its ends on a pin 82, the opposite end of the lever carrying trunnions 84 extending into a peripheral groove formed in the upper end of a plunger 86. This plunger projects upwardly from a piston movable vertically in a cylinder 88, as shown in detail in Patent No. 2,230,244 referred to above. Upon introduction of pressure fluid into the lower end of the cylinder 88 the lever 80 is rocked in a counterclockwise direction, causing the leveling roll 14 to be lifted against the action of the springs 64, 66.

Introduction of pressure fluid into the cylinder 88 is controlled by a valve 90, the lower end of which is connected by a pipe 92 with a pressure-regulating valve 94 arranged upon downward movement of a plunger 96 to direct fluid under pressure to the valve 90 from which it may be delivered to the cylinder 88 when the valve 90 is properly positioned. The construction of the valves 90, 94 is illustrated in the aforementioned patent to which reference may be had for a detailed description thereof although it is to be understood that in so far as the present invention is concerned, the valves need not be constructed precisely as shown in that patent. It will be understood that when the plunger 96 of the pressure-regulating valve 94 is in the position illustrated in Fig. 1 the discharge side of the pump by which pressure fluid is delivered to the various parts of the machine is by-passed to the fluid reservoir but when the plunger 96 is depressed, this by-pass is cut off and fluid at sufficiently high pressure to operate the various instrumentalities of the machine is delivered by the pump. The

valve 90 has a stem 98 arranged so that when the stem is in its upper position as shown in Fig. 1 the valve permits delivery of pressure fluid from the valve 94 to the cylinder 88 but when the stem 5 is depressed, the flow of pressure fluid to the cylinder 88 is cut off and the cylinder is allowed to exhaust. Thus it will be understood that as soon as the plunger 96 is depressed at the beginning of the leveling operation in a manner to be 10 described, pressure fluid flows into the valve 90 and thence to the cylinder 88 acting to hold the leveling roll in an elevated position against the action of the springs 64, 66. Subsequently the stem 98 of the valve 90 is depressed and the cylinder 15 88 exhausts whereupon the leveling roll 14 is forced downward into engagement with the shoe bottom by the springs 64, 66.

To the upper end of the plunger 96 is connected a link 100, the upper end of which is pivoted to the lower end of a depending arm 102 carried by 20 a rockshaft 104 journaled in the frame of the machine. The link 100 and the arm 102 form a toggle which is straightened upon clockwise movement of the arm 102 thereby to move the 25 plunger 96 downwardly operating the pressure-regulating valve to supply pressure fluid to the cylinder 88 as well as to the fluid-pressure motors for operating the jack and tipping the leveling roll as described in the aforementioned patent. 30 The toggle 100, 102 is straightened upon rearward movement of the shoe support to carry the shoe beneath the leveling roll by mechanism which will now be described. Secured to the rock-shaft 104 is a downwardly extending arm 106 the lower end 35 of which is secured to a bearing for a block recessed to straddle a bushing 108 which is fast on a rod 110 mounted for sliding movement forwardly and rearwardly of the machine. Slidable on the rod 110 is a bushing 112 urged forwardly 40 along the rod by a spring 114, the rearward end of which engages a collar 116 secured to the rod. The arrangement is such, as disclosed more fully in the Hart Patent No. 2,230,244, that upon forward movement of the rod 110 the spring 114 45 acts on the bushing 112 and the block at the lower end of the arm 106 to swing the toggle links 100, 102 into substantial parallel relation. As the toggle links are thus swung the plunger 96 is moved downwardly operating the pressure-regulating valve 94 supplying pressure fluid to the cylinder 88.

The forward end of the rod 110 is pivoted at 50 120 to an arm 122 secured to a rockshaft 124 carried by the frame of the machine. Also secured to the rockshaft 124 is an upwardly extending arm 126 carrying at its upper end a roll 127 engageable with a downwardly extending arm 128 carried by the shoe support 10. The rod 110 carries a lock nut 130 forming an abutment for 55 one end of a coil spring 132 surrounding the rod, the other end acting against a fixed stop 134 on the machine frame. The spring 132 urges the rod 110 forwardly holding the roll 127 at the upper end of the arm 126 in engagement with the 60 arm 128 carried by the shoe support. Upon rearward movement of the shoe support to carry the shoe into operative relation to the leveling roll the arm 128 moves forwardly whereupon the spring 132 causes forward movement of the rod 65 110 to straighten the toggle 100, 102. Pressure fluid is accordingly applied to the cylinder 88 to hold the leveling roll in an elevated position against the action of the springs 64, 66 to permit movement of the toe end of the shoe thereunder, 70 110 to straighten the toggle 100, 102. Pressure fluid is accordingly applied to the cylinder 88 to hold the leveling roll in an elevated position against the action of the springs 64, 66 to permit movement of the toe end of the shoe thereunder, 75 the roll having been held in such position at the

conclusion of a leveling operation by mechanism to be described.

At a predetermined point in the forward movement of the rod 110, during movement of the shoe support to carry the shoe beneath the leveling roll the valve 90 is operated to cut off the flow of fluid into the cylinder 88 and to exhaust fluid therefrom, so that the roll is forced by spring pressure into engagement with the shoe bottom. This operation of the valve 90 is effected by a lever 136 connected by links 138 to the valve stem 98. The lever 136 is pivotally carried by a pin 140 and has an upwardly extending arm 142 carrying an eye bolt 144 to which is connected one end of a spring 146, the other end being connected to a pin 148 carried by the frame of the machine. The rod 110 carries an abutment 150 which acts on a downwardly extending arm 152 of the lever 136 to move the lever in a clockwise direction against the action of the spring 146 at a predetermined point in the forward movement of the rod. The abutment 150 is adjustably positioned lengthwise of the rod so that it will act to move the lever 136 at the time when the toe end of the shoe moves under the roll 14 whereupon the roll is moved by spring pressure against the shoe bottom. At any time during the leveling operation the operator, by stepping on a treadle 154, can impart rearward movement to the rod 110 sufficient to operate the valve 90 and lift the roll. This treadle is pivoted at 156 to the base of the machine and is normally held in the up position shown in Fig. 1 by a spring 158, the upper position of the treadle being determined by a stop screw 160. Pivoted to the treadle 154 is a bar 162 having a slot 164 in its upper end arranged to receive a pin 166 carried by an arm 170 secured to the shaft 124. By depressing the treadle 154 the shaft 124 is rotated in a clockwise direction causing rearward movement of the rod 110 and operation of the lever 136 to operate the valve 90 admitting pressure fluid into the cylinder 88 to lift the leveling roll.

With the jack in its forward position, as shown in Fig. 1, and the valve 94 positioned to by-pass pressure fluid from the discharge side of the pump to the fluid reservoir, the springs 64, 66 act to move the roll 14 downwardly. If this movement of the roll is permitted there is a danger that the toe end of the shoe may engage the roll 14 before the roll lifts to permit passage of the shoe thereunder. This possibility exists because of the fact that a slight time elapses after the beginning of the rearward movement of the shoe support and the operation of valve 94 with the consequent introduction of pressure fluid into the cylinder 88 to lift the leveling roll. If the operator moves the shoe support rearwardly at a high enough rate of speed the toe end of the shoe may move into contact with the roll before the roll has been lifted out of operative relation thereto. This may also happen if the toe end of the shoe is jacked somewhat forwardly of the proper position with respect to the shoe support. In order to prevent this accidental engagement of the toe end of the shoe with the leveling roll provision is made for maintaining the leveling roll in an elevated position into which it is moved during forward movement of the shoe support into the position shown in Fig. 1.

Carried by the arm 48 is a pin 172 which, during the leveling operation, rides in a slot 174 (Fig. 2) in an arm 176 connected by a pivot pin 178 to a link 180 which is in turn pivoted at 182 to an arm 184 extending vertically from the pivot 70. 75

With the parts in the positions shown in Fig. 2 the slot 174 is concentric with respect to the shaft 46 so as not to interfere with the rocking movements of the arm 48 necessary to permit heightwise movements of the leveling roll 14 as it traverses the bottom of the shoe during the leveling operation. It will be observed that the arm 176 and link 180 form a toggle which is straightened by upward movement of a rod 186 connected 10 to the pin 178 forming the knee of the toggle. When the toggle is thus straightened as shown in Fig. 1, the arm 176 to the right of the slot 174 acts on the pin 172 to prevent clockwise movement of the arm 48 thereby holding the bushing 44 against rearward movement along the shaft 24 and holding the leveling roll 14 in the elevated position shown in Fig. 1, against the action of the springs 64, 66. An adjustable stop screw 188, threaded through the frame of the machine, 15 engages the adjacent portion of the arm 184 to adjust its position and that of the toggle whereby the position in which the roll 14 is held when the jack is in its forward position may be varied.

The lower end of the rod 186 is pivoted at 190 to an arm 192 of a bell crank lever 194 pivoted at 196 to a bracket 198. A spring 200 acts on the arm 192 of the bell crank lever to pull the rod 186 downwardly thereby breaking the toggle and moving the arm 176 into the position shown in Fig. 2. 20 The extent of movement of the parts is limited by the engagement of the rearward end of the arm 192 of the bell crank lever with an adjustable stop screw 204.

In order to move the bell crank lever 194 in a counter-clockwise direction to straighten the toggle, as shown in Fig. 1, an arm 206 of the lever has pivoted thereto a rod 208 having fast thereon a collar 210 intermediate the ends of the rod which is slidably received in a sleeve 212. This sleeve is secured by a pin 214 to a block 216 pivoted on an arm 218 secured to the shaft 12. With the parts in the positions illustrated in Fig. 1, the bell crank lever 206 is held, as shown, by the engagement of the collar 210 with the rearward end 45 of the sleeve 212. Upon rearward movement of the shoe support to carry the shoe beneath the leveling roll the arm 218 moves in a clockwise direction which moves the sleeve 212 forwardly permitting the rod 208 to move in the same direction under the force exerted by the spring 200 acting on the bell crank lever 194 thereby moving the parts into the positions shown in Fig. 2. The slot 174 in the arm 176 is now concentrically disposed with respect to the shaft 46 so that the 50 leveling roll may move vertically in accordance with the contour of the shoe bottom during the leveling operation. Upon completion of the leveling operation and movement of the shoe support back to the position shown in Fig. 1 the sleeve 212 moves rearwardly engaging the collar 210 and turning the bell crank lever 194 in a counter-clockwise direction thereby moving the rod 186 upwardly to straighten the toggle links. This action of the arm 176 of the toggle operates through the pin 172 to hold the arm 48 in the position shown thus holding the leveling roll in the elevated position shown in Fig. 1.

The timing of the operation of the toggle 176, 180 is so related to the operation of valves 90, 94 that the toggle modifies the actions of the valves only while the shoe support is in its forward position. The valve 94 is operated by the time in the rearward movement of the support when the toggle is broken, and because the roll is in an elevated position, no lifting of the roll against the

action of springs 64, 66 is required at this time and the pressure fluid is able to maintain the roll in its elevated position until the valve 90 is operated, permitting the roll to be moved by spring pressure into engagement with the shoe bottom. At the conclusion of the leveling operation, valve 90 operates to cause lifting of the roll, and the toggle 176, 180 is straightened to hold the roll in its elevated position before toggle 100, 102 is broken to operate the pressure regulating valve 94 causing fluid from the outlet side of the pump to be by-passed to the reservoir.

Having thus described my invention, what I claim as new and desire to secure by Letters Patent of the United States is:

1. In a leveling machine, a shoe support, a leveling roll, means mounting said support for movement in directions lengthwise of a shoe thereon to cause the leveling roll to operate progressively along the shoe bottom, spring means for pressing the leveling roll against the bottom of the shoe, means operative in response to forward movement of the shoe support to carry the shoe out of operative relation to the roll for lifting said roll against the action of said spring means, and means controlled by said shoe support for locking the roll in its elevated position with the shoe support located forwardly of the roll.

2. In a leveling machine, a shoe support, a leveling roll, means mounting said support for movement in directions lengthwise of a shoe thereon to cause the leveling roll to operate progressively along the shoe bottom, spring means for pressing the leveling roll against the bottom of the shoe, means for locking said roll in an elevated position above the shoe bottom, means normally rendering said locking means ineffective, and means operated by said shoe support upon movement thereof to carry the shoe forwardly of the leveling roll for operating said locking means.

3. In a leveling machine, a shoe support, a leveling roll, means mounting said support for movement in directions lengthwise of a shoe thereon to cause the leveling roll to operate progressively along the shoe bottom, spring means for pressing the leveling roll against the bottom of the shoe, a toggle, means operated by said toggle when in straightened position for holding said roll in elevated position above the shoe bottom, means operated by said shoe support in response to its movement to carry the shoe forwardly of said leveling roll for straightening said toggle, and spring means acting on said toggle to break it.

4. In a leveling machine, a shoe support, a leveling roll, means mounting said support for movement in directions lengthwise of a shoe thereon to cause the leveling roll to operate progressively along the shoe bottom, spring means for pressing the leveling roll against the bottom of the shoe, fluid-pressure means for lifting the roll against the action of said spring means in response to forward movement of the support to carry the shoe out of operative relation to said roll, and means controlled by the shoe support when in its forward position for locking said roll in the position to which it is moved by the fluid-pressure means.

15. 5. In a leveling machine, a shoe support, a leveling roll, means mounting said support for movement in directions lengthwise of a shoe thereon to cause the leveling roll to operate progressively along the shoe bottom, spring means for pressing the leveling roll against the bottom of the shoe, fluid-pressure means for lifting the roll against the action of said spring means in response to forward movement of the support to carry the shoe out of operative relation to said roll, means rendering said fluid-pressure means ineffective to maintain the roll in elevated position with the shoe support in its forwardmost position, and means controlled by the shoe support when in its forwardmost position for locking the roll in the position to which it is moved by said fluid-pressure means.

30. 6. In a leveling machine, a shoe support, a leveling roll, means mounting said support for movement in directions lengthwise of a shoe thereon to cause the leveling roll to operate progressively along the shoe bottom, spring means for pressing the leveling roll against the bottom of the shoe, fluid-pressure means for lifting the roll against the action of said spring means in response to forward movement of the support to carry the shoe out of operative relation to said roll, a toggle, means operated by said toggle when in straightened position for holding said roll in the position to which it is moved by said fluid-pressure means, means operated by said shoe support in response to its movement to carry the shoe forwardly of said leveling roll for straightening said toggle, and spring means acting on said toggle to break it.

FRED V. HART.
